UNITED STATES PATENT OFFICE.

WILLIAM A. HAAS, OF COUNCIL BLUFFS, IOWA.

PAPER-HANGER'S RULE.

Application filed September 28, 1928, Serial No. 308,978.

The invention relates to paper trimming rules especially those in general use for trimming the margin from wall paper in paper hanging.

5 A further object is to provide a device of this character that can be readily adjusted without loss of time, and with such precision and convenience that a single movement thereof will aline the edge of the rule through 10 its full length upon the margin line of the paper without the operator changing his position.

A further object is to provide a device of this character in such relation to a paper 15 pasting board that it may be readily folded out of the way for pasting and other operations when not in use during the act of trimming.

20 A further object is to provide a straight edge that may be used in connection with a conventional form of slidable circular paper trimming knife.

A further object is to provide a paper trimming ruler having pivoted upon its upper 25 face adjacent its opposite ends projecting arms susceptible of horizontal swinging movement having their forward portion bifurcated and hingedly pivoted at their outer ends, over the upper end of depending shafts 30 rotatably and slidably engaged within upright sleeves which sleeves are rigidly attached at their lower extremities to the outer ends of forwardly extending bars having their inner ends slidably engaged within sus- 35 taining guides secured to the underside of a conventional paper hanger's pasting board.

With the above and other objects in view the invention resides in the combination and arrangement of parts as hereinafter set forth, 40 shown in the drawing, described and claimed, it being understood that changes in the precise embodiment of the invention may be made within the scope of what is claimed without departing from the spirit of the in- 45 vention.

In the drawing:

Figure 1 is a top view of the rule and a portion of the pasting board, upon which it is mounted.

50 Figure 2 is an enlarged view of one end of the pasting board and the upper side of on end of the rule together with an upper side view of one member of the rule alining device.

55 Figure 3 is an end view of the ruler, a portion of the board and the alining device.

Figure 4 is an end view of a portion of the board and the alining device showing their relative normal position when folded to inoperative position.

Figure 5 is a perspective view of one of the guides in which the supporting bars are slidably mounted and clamped.

Figure 6 is an end view of the pasting board showing a recess below designed to contain the ruler when the said board is folded for 65 transportation.

Referring to the drawing, the numeral 1 designates a paper hanger's pasting table, which table is preferably formed from two longitudinal sections hingedly connected at 70 1^a whereby they may be folded onto each other for compactness for shipping and storage purposes. The under sides of the table sections are provided with recesses 1^b which register when the sections are folded onto 75 each other and form a longitudinal chamber for the reception of the straight edge and rule hereinafter set forth. Extending upwardly from one edge of the table is a bead 2, against which the strip of wallpaper engages for properly alining the same when placed on the table. Disposed on the table 1 is the combined straight edge and rule 3, under which the paper is placed, and on one edge of which a scale 4 is printed or stamped so that the 80 operator may utilize the same for measuring purposes. The upper face of the straight edge is provided with a guide groove 5 for guiding a cutter for trimming the edge of wallpaper beneath the straight edge. Pivotally mounted on the upper face of the straight edge, adjacent its end, are triangularly shaped plates 6, one of the ends of which is pivoted on the bolts 7 and held against pivotal movement by wing nuts 8, while the 85 other ends of the plate are provided with arcuate slots through which bolts 10 extend, said slots being designated by the numeral 90 11.

The plates 6 are held against pivotal movement by means of wing nuts 9^a, threaded on the bolts 10. Pivotally connected at 12 to the plates 6 are outwardly extending arms 12^a, the outer ends of which terminate in bifurcations 13, which are pivotally connected to the heads 14 of downwardly extending shafts 15, and which shafts are rotatably mounted in upwardly extending sleeves 16 carried by the outwardly adjustable arms 17. Arms 17 extend inwardly and are slidably mounted in guides 18 in the under side of the paste board, 110

and it will be seen by adjusting the set screw 19 that the arms 17 may be securely clamped in any outward or inward adjusted position. It will also be seen that by pivotally adjusting the plates 6 the straight edge and rule may be adjusted inwardly or outwardly to various positions, and by providing the rotatable shafts 15 and pivotal connections 12, the straight edge may be adjusted inwardly or 10 outwardly in parallel relation to the bead 2 for properly positioning the same in relation to a predetermined position for severing the wall paper held beneath the straight edge.

When the straight edge is not in use it assumes the position shown in Figure 4, and at which time it will be noted that it hangs downwardly in substantially a vertical plane and the bifurcation 13 is sufficiently large whereby it will receive therein the sleeve 16 20 and the end of the adjustable arm 17.

From the above it will be seen that a paper hanger's straight edge is provided which may be easily moved to operative position or folded to inoperative position and when the device 25 vice is removed it may be placed in recesses between the board sections for shipping and storage purposes.

The invention having been set forth what is claimed as new and useful is:—
30 1. A parallel alining device in combination with a paper hanger's pasting board comprising a paper trimming guide rule carried in

parallel relation to said board upon the upper side thereof, arms pivoted adjacent opposite ends of said rule, sleeved shafts hingedly carrying the outer ends of said arms, vertically disposed sleeves engaging the said shafts, horizontal bars integrally supporting the lower ends of said sleeves at right angles thereto, and sustaining guides disposed upon the lower side of said board and slidably engaging the said bars. 35

2. A parallel alining device in combination with a paper hanger's pasting board, comprising a paper trimming guide rule carried 40 in parallel relation to said board upon the upper side thereof, arms pivoted adjacent opposite ends of said rule, sleeved shafts hingedly carrying the outer ends of said arms, vertically disposed sleeves engaging the 45 shafts, horizontal bars integrally supporting the lower ends of said sleeves at right angles thereto, sustaining guides disposed upon the lower side of said board and slidably engaging said bars, said arms being carried by 50 plates pivoted at one end to said rule and having a slot adjacent the opposite end adjustably engaging an upwardly extended bolt protruding from said rule and engaging a threaded locking nut at its upper end. 55

In testimony whereof I heretunto affix my signature.

WILLIAM A. HAAS.
